(57) **CLAIM**

The ornamental design for a balaclava with detachable dust mask, as shown and described.

DESCRIPTION

FIG. 1 is a perspective view of a balaclava showing my new design;

FIG. 2 is a front elevational view thereof;

FIG. 3 is a left side elevational view thereof;

FIG. 4 is a rear elevational view thereof;

FIG. 5 is a top plan view thereof; and,

FIG. 6 is a front elevational view of a detachable dust mask thereof.

The tag or label is shown in broken lines in FIGS. 2 and 3 for illustrative purposes only as the tag/label forms no part of the claimed design.
